FINISHING TOOL FOR TUBULAR STEREO-
TYPE PLATES

Herbert James Lowe, Galesburg, Ill.

Application April 4, 1931. Serial No. 527,808

1 Claim. (Cl. 29—21)

This invention relates to a finishing tool for shaping the edges of tubular stereotype plates whereby they can be held down to an intermediate portion of a cylinder. Tubular stereotype plates as now produced have no means whereby 5 the abutting edges of two plates, such as used when running double pages, can be fastened to the cylinder. Ordinarily the pressman has the plates delivered to him with the ends merely abutting. Consequently as there is nothing to hold these meeting ends to the cylinder they frequently spring outwardly and cause considerable noise by continual slapping upon the cylinder as they rapidly rotate during the printing operation.

It is an object of the present invention to provide a tool whereby the ends of the tubular stereotype plates can be shaped to receive a fastening means for keying them to the cylinder.

It is a further object to provide a novel means for holding the plates to a cylinder.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, 30 without departing from the spirit of the invention.

In the accompanying drawing, the preferred form of the invention has been shown.

In said drawing:

Figure 1 is a front elevation of the tool constituting the present invention.

Figure 2 is a section on line 2—2, Figure 1, the bit being shown in engagement with a portion of a tubular stereotype plate.

Figure 3 is a plan view of the bit.

Figure 4 is an end elevation thereof.

Figure 5 is a section on line 5—5, Figure 4.

Figure 6 is a section through a portion of a cylinder and of two abutting stereotype plates held to the cylinder by a clamp or key.

Referring to the figures by characters of reference, 1 designates a collar which is adapted to be placed on the boring shaft of the usual tubular stereotype plate finisher and it is held to this shaft by a set screw 2 bearing against a block 3 adapted to engage the shaft. This block may be held against displacement when the tool is off of the shaft by a loose pin 4 extending 55 thereinto from the collar.

A plate 5 is attached to one face of the collar and extends across one end of a dovetail groove 6 formed in the periphery of said collar parallel with the axis of rotation of the collar. A screw 7 is swiveled in the plate 5 and is provided at one end with a head 8 of any suitable construction whereby it can be rotated readily. This screw projects into and engages a screw-threaded bore 9 formed in a slide 10 which fits snugly in groove 6. That end of the slide remote from plate 5 has an angular opening or socket 11 the wall of which carries a set screw 12.

The bit or cutting tool of the device includes a shank 13 angular in cross section and adapted to fit snugly in socket 11. This shank can be 70 adjusted longitudinally of the socket and held securely by the set screw 12.

At the outer end of the shank is a head 14 having three cutting edges indicated at 15, 16 and 17 respectively. All of these cutting edges lie in the same plane. The cutting edge 15 is perpendicular to the longitudinal axis of shank 13. The cutting edge 16 is parallel with said axis and at right angles to the edge 15, these two edges coming together to form a right angle as shown. The edge 17 is inclined at an acute angle relative to the edge 16.

After this tool has been secured on the shaft of the finisher the tubular stereotype plate is rotated and the tool gradually fed thereinto. 85 This will cause the edges 16 and 17 to form a V-shape groove G in the plate P while the end of the plate will be squared by the other cutting edge 15. The other tubular stereotype plate is similarly finished so that when the 90 grooved edges of the plates are brought together on a cylinder C, as shown in Figure 6, an interior annular dovetail groove will be provided in which will be seated a dovetail key or clamp 18 carried by the cylinder. This clamp can be 95 in the form of a split ring or an arcuate strip suitably fastened to the cylinder. Obviously with the meeting ends of the plates thus held they cannot spring nor can they slap upon the cylinder.

It is intended to bevel the outer ends of the plates and fasten them to the cylinder by means of the usual clamps.

While this invention has been shown and described for use with tubular or cylindrical plates it is to be understood that it can also be employed in the mounting of semi-cylindrical plates or plates of other curvatures used in rotary presswork.

What is claimed is:

A tool of the class described including a collar, means for fastening the same on a stationary boring shaft, there being a longitudinal 5 guide groove in the outer surface of the collar, a member fixed relative to the collar at one end of said groove, a slide in the groove having an angular socket in one end, an adjusting screw engaged in the other end of the slide 10 and swiveled in the plate, and an adjustable

bit for squaring and grooving the end of a rotating tubular stereotype plate, said tool including a shank fastened in the socket, and a head on the shank having a cutting point with cutting edges converging thereto away from the shank and another cutting edge perpendicular to one of the diverging edges and to the longitudinal center of the shank.
